UNITED STATES PATENT OFFICE.

JOE M. CATTOOR, OF EATON, COLORADO.

ROPE MACHINE.

Application filed May 23, 1921. Serial No. 471,637.

To all whom it may concern:

Be it known that I, JOE M. CATTOOR, a citizen of the United States, residing at Eaton, in the county of Weld and State of Colorado, have invented certain new and useful Improvements in a Rope Machine; and I do hereby declare the following to be a full, clear, and exact description of the invention, such as will enable others skilled 10 in the art to which it appertains to make and use the same.

The object of the invention is to provide a simple and efficient means for manually constructing twisted rope of various thicknesses to suit the purpose for which it is designed and any desired length and any preferred materials; and with this object in view the invention consists in a construction and combination of parts of which a preferred embodiment is shown in the accompanying drawings, wherein:

Figure 1 is a view of the apparatus showing the relation of the parts when the strands are first applied thereto ready for 25 twisting.

Figure 2 is a similar view showing the follower advanced a portion of the distance between the anchoring member and the twisting member.

Figure 3 is a detail view in perspective and enlarged of the anchoring member.

Figure 4 is a plan view of the follower.

Figure 5 is a side view partly in section of the twisting member.

Figure 6 is a face view of the twister head.

Figure 7 is a sectional view on the plane indicated by the line 7—7 of Figure 5.

Figure 8 is a section on the plane indicated by the line 8—8 of Figure 5, and

Figure 9 is a view illustrating the manner in which the device is used to twist a short length of rope.

The apparatus consists essentially of a twister member 10 and an anchor member 11, the latter consisting primarily of a hook 12 swiveled as at 13 in a looped keeper 14 provided with an eye or opening 15 adapted for engagement with a supporting nail 16 or any other object by which it may be held

50 in a fixed position subject to the strain of twisting the rope. Associated with the hook 12 and forming a part of the anchoring member is a hanger loop 17 pivotally mounted as at 18 upon the keeper 14 and having 55 separable aligned terminals 19 yieldingly held by the resilience of the hanger in ter-

75 minal contact and adapted to combine when in their normal position to form a pivot for a follower plate 20 provided with a series of strand seats 21 of which four are shown 60 on the drawing and diametrically opposite radial extensions constituting arms 22, adapted for use as hereinafter fully explained, the center of the plate constituting the follower being upstruck to form a rib 65 23 provided at its terminals with openings 24 for the reception of the terminals 19 of the hanger loops as indicated in Figure 1.

The twister member consists essentially of a twister head 25 having a spindle 26 provided at its outer end with a crank arm 27 fitted with a revoluble grip 28, a sleeve 29 of tubular form constituting a bearing for the spindle and a handle 30 mounted exteriorly upon the sleeve.

75 The head 25 consists of the complementary disks 31 and 32 of which the latter is provided with a central threaded or tapped opening 33 for engagement by the threaded extremity of the sleeve 29, said disks being 80 provided with a plurality of sets or pairs of registering bearings in which are fitted the stems 34 of the twister hooks 35, the latter being pivoted as at 36 to the stems. The disks 31 and 32 are connected together 85

by screws 31^a. The inner ends of the stems are headed as at 37 and between the planes of the complementary disks forming the elements of the twister head are provided with keys 38 for engagement with corresponding notches in pinions 39 which are in engagement with a gear 40 keyed as at 41 to the spindle 26. The direction of rotation of the gear and pinions and hence of the twister hooks is controlled by ratchet mechanism consisting of a reversible pawl 42 pivoted as at 43 upon one of the disks of the head for engagement with the peripheral teeth of the main gear 40, the outer end or tail of the pawl as shown at 43 being connected with an actuating spring 44 having a terminal clip 45 adapted by engagement with opposite ends of the slot 46 in the flange of the disk 31 to reverse and yieldingly hold the pawl in such relation with the gear 40 as to permit rotary movement thereof in only one direction. The extremity of the spindle 26 is mounted in a central bearing 47 in the disk 31.

100 Fitted upon the end of the handle adjacent to the head is a ferrule 48 upon which is mounted a finger slide or push button 49

held in place by a guide pin 50 engaging a longitudinal slot 51 and terminally adapted for engagement with a seat 52 in the disk 32 to lock the twister head against rotation 5 relative to the handle 30.

A suspending loop or ring 53 is preferably mounted upon the end of the spindle 26 for supporting the twister head during the laying on or arrangement of the strands which 10 are to form the rope and which at the opposite end are engaged with the swivel hook 12.

The apparatus illustrated is provided for a four strand rope and obviously any desired number or bulk of fibres may be used in the 15 formation of each strand, it being preferable to have all of the strands of a uniform thickness but the selected thickness being such as to provide a rope of the required strength and diameter. The anchoring and 20 twisting members being suitably supported at the desired interval apart, the strands may be engaged respectively with the anchoring hook and the twister hook, the hanger loop 17 being meanwhile allowed to 25 hang freely downward out of the way as indicated by dotted lines in Figure 1, and after the strands have been arranged the follower head or plate 20 should be introduced between the strands, so that each strand oc- 30 cupies one of the seats 21 and the terminals 19 of the hanger loop should then be separated and engaged with the openings 24 to hold the follower head in a fixed position.

The controlling pawl 42 then being ar- 35 ranged in the desired position, according to the direction in which the rope is to be twisted, the handle 30 should be grasped in one hand and the crank grip in the other and the crank should be turned to cause rotary 40 movement of the twister hooks until the required tightness of twist of the strands has been attained. Then continuing the twisting operation, the follower head should by an attendant or assistant be disengaged from 45 the hanger loop and slowly advanced by means of the radial grips 22 toward the twister head, obviously permitting the strands to intertwist in rear thereof as indicated in Figure 2 of the drawing until the 50 follower head has reached a position in contact with the hooks of the twister head. This operation produces a hard rope of uniform twist and tightness, similar in every respect to that which is produced by 55 machinery.

Should a short length of rope be desired, the anchoring member may be dispensed with, the ends of the strands remote from the twister head being engaged with a nail 60 or stationary hook of any desired form, and after the twisting of the strands has been completed in accordance with the above description the push button 49 may be moved to release the twister head to permit it to ro- 65 tate under the influence of the twist which

has been imparted respectively to the strands, the turning of the spindle however being continued throughout this twisting movement of the head so as to insure a proper intertwisting of the strands while 70 maintaining the tightness of the twist of the strands individually. The last named arrangement and use of the apparatus are indicated in Figure 9.

Having thus described the invention, what 75 I claim is:—

1. A rope machine having an anchoring member and a twisting member, the latter having a twister head, a plurality of twister hooks for respective engagement with the 80 strands to be twisted, an operating spindle, gear connections between the spindle and said twister hooks, a handle journaled on said spindle, and means to connect the handle for unitary movement with the head 85 and spindle.

2. A rope machine having an anchoring member and a twisting member, the latter having a twister head, a plurality of twister hooks for respective engagement with the 90 strands to be twisted, an operating spindle, and gear connections between the spindle and said twister hooks, the twister head being carried by a sleeve fitted upon the spindle, a handle revolvably mounted upon the 95 sleeve and means for locking the handle to the twister head.

3. A rope machine having an anchoring member and a twisting member, the latter having a twister head, a plurality of twister 100 hooks for respective engagement with the strands to be twisted, an operating spindle, and gear connections between the spindle and said twister hooks, the twister head being carried by a sleeve revolvably mounted 105 upon the said spindle and means for securing the twister head against rotation during the operation of the twister hooks.

4. A rope machine having an anchoring member and a twisting member, the latter 110 having a twister head, a plurality of twister hooks for respective engagement with the strands to be twisted, an operating spindle, and gear connections between the spindle and said twister hooks, the twister head being carried by a sleeve revolvably mounted upon said spindle, a handle in which the tread sleeve is revolvably fitted and which carries a terminal ferrule, and a locking device mounted upon the ferrule for engagement with the twister head to secure the latter against rotation during the operation of the twister hooks.

5. A rope machine having an anchoring member and a twisting member, the latter 115 having a twister head, a plurality of twister hooks for respective engagement with the strands to be twisted, an operating spindle and gear connections between the spindle and said twister hooks, said connections 120

- having a main gear actuatable by the spindle and pinions carried by the stems of the twister hook and engaged with said main gear, and a reversible ratchet means for determining the direction of rotation of said gear.
6. A rope machine having an anchoring member and a twisting member, the latter having a twister head, a plurality of twister hooks for respective engagement with the strands to be twisted, an operating spindle, and gear connections between the spindle and said twister hooks, said gear connections having a main gear carried by the spindle, pinions carried by the stems of the twister hook in mesh with said main gear, and ratchet mechanism consisting of a reversible pawl engaged with the main gear and having an actuating spring provided with a clip for reversible engagement with the twister head.
7. A rope machine having an anchoring member for the strands, a follower for said strands, and a separable connection between
- said anchoring member and said follower whereby the latter may be released for movement along said strands.
8. A rope machine having an anchoring member for the strands, a follower having teeth to receive said strands, handle means for said follower, and a separable connection between said anchoring member and said follower whereby the latter may be released from movement along said strands.
9. A rope machine having an anchoring member for the strands provided with a resilient loop, the follower for the strands, said loop having separable terminals to separably engage the follower, whereby said follower may be released for movement along said strands.

In testimony whereof I affix my signature in presence of two witnesses.

JOE M. CATTOOR.
